UNITED STATES PATENT OFFICE.

HERMAN L. MEYER, OF ST. PAUL, MINNESOTA.

FURNACE.

SPECIFICATION forming part of Letters Patent No. 718,497, dated January 13, 1903.

Application filed April 24, 1902. Serial No. 104,427. (No model.)

To all whom it may concern:

Be it known that I, HERMAN L. MEYER, a citizen of the United States, residing at St. Paul, in the county of Ramsey and State of Minnesota, have invented certain new and useful Improvements in Furnaces, of which the following is a specification.

My invention relates to improvements in furnaces.

10 The object of my invention is to provide means applicable to boilers for creating better combustion of fuel than heretofore, and thereby reducing the amount consumed and preventing the formation of smoke, as with 15 ordinary furnaces now in use.

This invention relates more particularly to that class of furnaces in which a stationary boiler is used and in which the draft is supplied by a current of air entering the fire-box.

20 My invention consists of the following parts, as hereinafter specified and claimed.

In the accompanying drawings, forming part of this specification, Figure 1 is a longitudinal section of my invention. Fig. 2 is a 25 section taken on the line X X of Fig. 1 looking toward the front of the boiler. Fig. 3 is a detail section showing the front of the boiler and one of the partitions between the flues. Figs. 4, 5, and 6 are detail views showing the method of constructing the partitions.

30 In the drawings, let A represent a boiler having the longitudinal flues 2.

B represents the furnace, having the brick walls 3 and 4, upon which the boiler is supported by means of the flanges 5 and 6 and the brackets 7 and 8. The flanges extend the entire length on each side of the boiler. The fire-box C is provided with the fire-grate D, to be hereinafter more particularly described. Fuel is supplied to the fire-grate through the door 9, and the ashes may be removed from the ash-pit 10 through the door 11. A draft-opening 12 enters the ash-pit below the grate through the wall 3. The bridge-wall E is positioned at the rear of the grate and below the boiler, so as to form the passage-way F for the products of combustion from the fire on the grate. The space between the front end 13, adjoining the rear of the fire-grate, and the

45 back end 14, near the rear end of the boiler, is filled with sand and covered by a facing of fire-brick 15. The object of the bridge-wall is to 50 form the passage-way F, so as to confine the

heat from the furnace in the passage-way close to the boiler and to contain residual 55 heat when the furnace is operated, so that should the fire die down or go out the boiler will be supplied with heat for a considerable time from the bridge-wall. The front end 13 of the bridge-wall projects at 16 above the 60 facing 15, and a plurality of air-inlet pipes 17, leading from below the fire-grate in the ash-pit to above the facing 15, back of the projecting portion 16, as shown in the drawings, are adapted to assist combustion of the 65 unconsumed products from the fire by feeding air from the inlet 12 to the passage-way F.

A dividing-wall G at the rear of the boiler, as shown in Fig. 1, is adapted to direct the 70 draft from the furnace through the lower portion 18 of the boiler-flues. This dividing-wall is hinged by means of the shaft 19, which is journaled in the walls 3 and 4 of the furnace. A corresponding dividing-wall is provided at the 75 front end of the boiler and is also hinged by means of the shaft 20 in a similar manner. The front dividing-wall directs the draft from the lower flues 18 into the longitudinal passage-ways I and J, extending along the sides of 80 the boiler and connecting with the upper portion 21 of the flues at the rear end of the boiler. These longitudinal passage-ways I and J are formed in the brickwork of the boiler-furnace immediately below the flanges 5 and 6 85 and have inlets at 22 and outlets at 23 for the draft. The draft continues from the passage-ways through the upper set of flues 21 and out by means of the chimney I at the front end of the boiler. This chimney, as shown, 90 is provided with the damper 24, so that the draft can be regulated in the chimney when desired. The inlet passage-way 12 is also provided with a damper 25 for regulating the inlet of air into the furnace. It is obvious 95 that a forced draft may be used when desired.

The dividing-walls G and H are constructed with a reverse curve, as shown in the drawings. The metal plate 26, forming the back 100 of the wall, is protected against damaging effects of the heat from the fire by means of a facing of fire-bricks 27, as shown. The bricks are fastened to the plate by means of the T-shaped ribs 28 on the lower surface 29. The 105 bricks are indented at 30, so as to engage the

T-shaped ribs, and are held from sliding off the ribs by means of the clips 31 on the plate. By reference to Figs. 4, 5, and 6 the construction of the dividing-walls may be followed. The shafts 19 and 20 of the dividing-walls are provided, respectively, with the handles 32 and 33 (see Figs. 2 and 3) for the purpose of turning the dividing-walls. The object of curving the plates 26, as shown, is for the purpose of dumping waste products of combustion that collect on the surface of the dividing-walls by turning the handles.

To more completely consume the waste products of combustion in the furnace, I have also provided a pair of air-inlet pipes 34 and 35, which rise vertically through the brick walls of the boiler-furnace from the ash-pit to the front ends of the longitudinal passage-ways I and J. These pipes are adapted to feed air into the longitudinal passage-ways.

As shown, the grate is constructed of longitudinal bars 31, which are adapted to rest on the shoulders 37 and 38. This portion of the grate is of ordinary construction. I preferably provide the open-grate-work sections 39 on each side and at the rear of the grate-bars 36. These sections incline upward from the bars 36, as shown in the drawings. The fire is preferably built on the grate-bars 36 and the grate-sections 39 left open, so that air is free to circulate around the fire to more completely aid combustion of the fuel.

Having described my invention, what I claim as new, and desire to protect by Letters Patent, is—

1. A boiler-furnace having a grate, a bridge-wall at the rear of said grate, forming a passage-way between its upper surface and the lower surface of the boiler, a plurality of air-inlet pipes communicating with said passage-way, a dividing-wall connecting said passage-way with the rear ends of part of the boiler-flues in the boiler, a corresponding dividing-wall at the front end of the boiler, a passage-way on each side of the boiler connecting the front ends of said portion of flues with the back ends of the remaining portion of flues, an air-inlet pipe leading to each of the side passage-ways, and means for regulating the supply of air through said inlet-pipes; all of said air-supply pipes adapted to discharge air to mingle with the products of combustion in the passage-ways.

2. In combination, a boiler having a plurality of sets of flues and a communication exterior to said boiler and between the ends of said sets of flues, for the purposes specified.

3. A boiler-furnace having a grate, an air-inlet below said grate, a bridge-wall at the rear of the grate, means for admitting air from said inlet below the grate into the passage-way formed by the upper surface of the bridge-wall and the lower surface of the boiler, a dividing-wall between the upper and lower flues at the rear end of the boiler, a corresponding dividing-wall between the upper

and lower flues at the front end of said boiler, and passage-ways leading from the flues below the corresponding dividing-wall to the back end of the flues above the rear dividing-wall.

4. A boiler-furnace having an ash-pit, a grate above said ash-pit, a bridge-wall at the rear of the ash-pit and grate, positioned so as to form a passage-way close to the lower surface of the boiler, an air-inlet below the grate, means for admitting air from said inlet below the grate to said passage-way, a system of dividing-walls between the flues of the boiler, and a passage-way exterior to said boiler and connecting the opposite ends of the flues separated by said system of dividing-walls.

5. A boiler-furnace having a grate, a bridge-wall at the rear of said grate forming a passage-way between its upper surface and the lower surface of the boiler, a system of dividing-walls arranged between the flues at each end of the boiler, communications outside the boiler which connect the opposite ends of the sets of flues, and air-inlet openings in said communications.

6. A boiler-furnace having a grate, a bridge-wall at the rear of said grate forming a passage-way between its upper surface and the lower surface of the boiler, dividing-walls arranged between the flues at each end of the boiler, and a longitudinal passage-way on each side of the boiler communicating the lower set of flues at the front end of the boiler with the upper set of flues at the opposite end, for the purposes specified.

7. A boiler-furnace having a grate, a bridge-wall at the rear of said grate, dividing-walls arranged between the flues at each end of the boiler, a longitudinal passage-way at the side of the boiler connecting the lower flues at the front end of the boiler with the upper flues at the opposite end, and means for admitting air into said longitudinal passage-way to mingle with the products of combustion.

8. A boiler-furnace having dividing-walls between its flues at its opposite ends, and exterior means for communicating the lower flues at the front end of the boiler with the upper flues at the opposite end, for the purposes specified.

9. A boiler-furnace, having dividing-walls between its flues at its opposite ends, communications between the lower flues at the front end of the boiler and the upper flues at the opposite end, and means for introducing air into said communications between said opposite ends of the boiler, for the purposes specified.

In testimony whereof I have signed my name to this specification in the presence of two subscribing witnesses.

HERMAN L. MEYER.
